(57) **CLAIM**

The ornamental design for an elbow-style water control valve, as shown.

DESCRIPTION

FIG. 1 is a front view of an elbow-style water control valve; FIG. 2 is a rear view of the elbow-style water control valve depicted in FIG. 1;

FIG. 3 is a left side view of the elbow-style water control valve depicted in FIG. 1;

FIG. 4 is a right side view of the elbow-style water control valve depicted in FIG. 1;

FIG. 5 is a top view of the elbow-style water control valve depicted in FIG. 1;

FIG. 6 is a bottom view of the elbow-style water control valve depicted in FIG. 1;

FIG. 7 is a top right perspective view of the elbow-style water control valve depicted in FIG. 1; and,

FIG. 8 is a bottom left perspective view of the elbow-style water control valve depicted in FIG. 1.
